CLAIM

(62) Division of application No. 29/507,641, filed on Oct. 29, 2014, now Pat. No. Des. 794,510.

The ornamental design for a motor scooter and/or toy replica thereof, as shown and described.

(51) **LOC (12) Cl.** **12-11**

DESCRIPTION

(52) **U.S. Cl.**

USPC **D12/110**

(58) **Field of Classification Search**

FIG. 1 is a top, front, and left perspective view of a motor scooter and/or toy replica thereof showing our new design; FIG. 2 is a top, rear, and right side perspective view thereof; FIG. 3 is a bottom, rear, and right side perspective view thereof;

USPC D12/109, 110, 111, 114, 117, 126, 184,

D12/186; D21/432, 458, 538

CPC B62D 37/00; B62D 57/00; B62K 9/00;

B62K 11/04; B62K 17/00; B62K 19/48;

B62M 7/12; F02B 61/02; A63H 17/21;

B62J 17/00; B62J 17/04; B62J 29/00

See application file for complete search history.

FIG. 4 is a right side elevation view thereof;

FIG. 5 is a bottom plan view thereof;

FIG. 6 is a front elevation view thereof;

FIG. 7 is a rear elevation view thereof;

FIG. 8 is a top plan view thereof; and,

FIG. 9 is a left side elevation view thereof.

The broken lines in the drawings illustrate portions of the motor scooter and/or toy replica thereof that forms no part of the claimed design.
